JOHN W CLARK
INVENTOR

By *Perley H. Plant*
ATTORNEY

UNITED STATES PATENT OFFICE.

JOHN W. CLARK, OF PROVIDENCE, RHODE ISLAND.

RAIL JOINT.

Application filed February 15, 1922. Serial No. 536,749.

To all whom it may concern:

Be it known that I, JOHN W. CLARK, a citizen of the United States, residing at Providence, in the county of Providence and 5 State of Rhode Island, have invented certain new and useful Improvements in Rail Joints, of which the following is a specification.

This invention relates to an improved 10 means for connecting the meeting ends of two railway rails in such a manner as to secure a high degree of flexibility at the junction of the rails, as well as to provide a support for the rail ends which will not be 15 subject to the usual distortion by reason of the constant wear occasioned by the passage of trains over the meeting ends of the rails.

One object of the invention is to provide 20 a trussed joint wherein the meeting ends of the rails are supported by a seat held in place by a truss member in such a manner as to overcome the excessive wear usually occasioned by the vibration of the rail ends, as well as to provide such an arrangement of the parts that the pressure exerted 25 upon the seat will be exerted substantially longitudinally of the truss member to avoid bending of the same and at the same time furnish a firm and flexible support.

Another object of the invention is to 30 provide a novel means for yieldably supporting the seat from the fish plates to hold the same constantly in contact with the meeting ends of the rails while permitting the 35 necessary movement of the seat due to the vibration of the rail ends.

A further object of the invention is to 40 provide an improved form of fish plate for resiliently engaging the opposite sides of the rails adjacent to their meeting ends, together with improved means for connecting the supporting seat to the fish plates whereby increased flexibility of the parts is secured.

Other objects and advantages of the 45 invention relate to certain improved details of construction and arrangement of the parts as will be more fully set forth in the detailed description to follow.

Referring to the drawings: 50
Fig. 1 is a side elevational view of the improved rail joint;

Fig. 2 is a top plan view of the truss member.

Fig. 3 is a side view of the truss member. 55

Fig. 4 is a transverse vertical sectional view, taken along the line 4—4 of Fig. 1.

Fig. 5 is a transverse vertical sectional view taken along the line 5—5 of Fig. 1.

Fig. 6 is a longitudinal vertical sectional 60 view taken along the line 6—6 of Fig. 4, and,

Fig. 7 is a longitudinal horizontal sectional view taken along the line 7—7 of 65 Fig. 1.

In the embodiment of the invention illustrated herewith 1 and 2 designate respectively adjacent rails the abutting ends of which are indicated by the numerals 3 and 4 respectively. The cross-ties supporting the end of the rail 1 are numbered 70 5 and 6, while the correspondingly positioned cross-ties for supporting the rail 2 are indicated by reference characters 7 and 8.

Fish plates 9 and 10, of symmetrical form 75 are positioned upon opposite sides of the meeting ends of the rails 1 and 2 and secured to each other through the web portions 11 of the rails by means of a plurality of bolts 12. Each of the fish plates is provided with a 80 thickened inner central portion 13, the thickened portions of the fish plates being located opposite each other and the meeting ends of the rails when the parts are in assembled position. The thickened portion 85

of each fish plate extends inwardly towards the rail web from the main body portion of the plate when the same is in operative position as shown in Fig. 7 of the drawings, whereby the thickened portion contacts directly with the rail and serves to a certain extent as a fulcrum about which the extremities of the plate are sprung into binding contact with the rail. Each of the fish plates is formed to provide throughout its 90 length the usual bearing head 14 and the usual inclined foot flange 15 for suitably engaging the head and base flange respec- 95

tively of each rail. A depending lug 16 is formed upon each of the fish plates centrally thereof and is inclined inwardly to contact at the lower end thereof with one 5 of the oppositely inclined ends 17 of a seat 18 positioned beneath the meeting ends of the rails. Each of the oppositely positioned depending lugs 16, is provided with an oblong opening 19 for the reception of a 10 screw 20 which is threaded into a suitable opening in the end of the seat 18.

A truss member 21, which may be of sufficient length to overlie two cross-ties upon each side of the rail joint, although it is capable of use when formed for attachment to one cross-tie only on each side of the rail joint, is positioned beneath the ends of the adjacent rails and provided with suitably positioned openings 22 for the reception of 20 screws 23 which may be threaded through the truss member 21 and into the cross-tie for securely anchoring the opposite ends of the truss member. The screws 23 employed for anchoring the truss member to the cross-ties nearest to the rail joint are preferably passed through or threaded in the base flanges 15 of the fish plates whereby the truss member is securely anchored to the fish plates as well as to the cross-ties, thus providing 25 an additional fastening means of a substantial character for holding the truss member securely in position. It is to be understood, however, that the threading of the screws 23 into the cross-ties is optional 30 and that a part or all of the screws may be replaced or supplemented by suitable fastening devices driven into the cross-ties, instead of threaded therein, or that any other suitable form of fastening devices may be 35 employed either as substitutes for or in conjunction with the screws 23 for suitably anchoring the ends of the truss member. The truss member 21 is provided adjacent the center thereof with inclined portions 24, and 40 a pair of oppositely positioned upturned lugs 25, which extend outwardly of and in registry with the downwardly extending lugs 16 carried by the fish plates. The lugs 25 are provided with openings 26 for the 45 reception of the screws 20 whereby the seat 18 is held in position beneath the meeting ends of the rails by attachment to both the lugs 16 and the lugs 25.

The central portion of the truss member 55 supports the seat 18 in position to contact with the meeting ends of the rails while permitting flexing of the parts as the weight of the train passes over the joint. By reason of the inclined portions 24 of the truss member adjacent to the seat the strain to which the truss member is subjected during the passage of a train over the joint is exerted substantially longitudinally of the truss member, and therefore any liability of 60 bending or distorting of the truss member is

avoided while resistance of the same to the strain is correspondingly increased. The truss member being securely anchored to the fish plates and cross-ties upon opposite sides of the rail joint acts as a cradle to adequately support the rail ends while permitting the necessary vibration of the rail ends without the consequent distortion of the seat generally resulting therefrom in devices of this character.

The oppositely positioned inclined lugs 16 carried by the fish plates engage the inclined ends 17 of the seat 18 adjacent to the lower side of the seat as shown in Fig. 4 of the drawings, and when the screws 20 are properly tightened the lugs 16 are placed under tension by pressure of the lugs 25 thereon so that they yieldingly urge the seat upwardly and into contact with the rail ends. This effect may be increased by forming the lower 70 ends of the lugs 16 somewhat thicker than the upper portions thereof as indicated at 27 whereby increased pressure upon the lugs 16 and the lower inclined ends of the seat 18 is obtained in tightening the screws 20. The provision of the oblong openings 19 in the lugs 16 permits slight vertical movement of the seat 18 upon vibration of the rail ends, while the tension upon the lugs 16 tends to return the seat into contact with the rail 80 ends as soon as the vibration of the rail ends has subsided. By means of this improved arrangement of the parts, especially when taken in connection with the improved form of fish plates employed, a joint is provided 90 which possesses a high degree of flexibility while at the same time the provision of the truss member firmly supports the parts in position thus combining to a high degree the necessary elements of strength and flexibility 95 requisite in devices of this character.

While I have described one form of my invention with considerable particularity in order to make clear to those skilled in the art a practical application of the same, I am 100 aware that various changes may be made in the details of construction and arrangement of the parts without departing from the spirit and scope of my invention and therefore I do not desire to be limited to the precise details of construction shown and described except as the same may be properly 110 embraced within the terms of the appended claims when broadly construed in the light of my invention.

What I claim is:

1. A rail joint comprising a pair of abutting rail ends, fish plates upon opposite sides of the rail ends, bolts passing through said rail ends and fish plates, a resiliently supported seat positioned beneath the meeting points of said rail ends, a truss underlying said seat to support the same from points remote from the meeting ends of said rails and provided with upturned lugs adjacent 125

to the opposite ends of said seat, and means for connecting said lugs to said seat.

2. A rail joint comprising a pair of abutting rail ends, fish plates upon opposite sides 5 of the rail ends, bolts passing through said rail ends and fish plates, a seat for the meeting ends of said rails, a truss member anchored at points located upon opposite sides of said seat and flexibly supporting the seat 10 in contact with the meeting ends of said rails, said truss member being provided with portions overlying the ends of said seat, and means for securing said seat to said overlying portions.

15 3. A rail joint comprising a pair of abutting rail ends, fish plates upon opposite sides of the rail ends provided with oppositely positioned downwardly extending lugs, a seat positioned between said lugs and resiliently 20 supported thereby in contact with the base of said rail ends, and additional means for supporting said seat to permit flexing of the same upon movement of said rail ends.

4. A rail joint comprising a pair of 25 abutting rail ends, fish plates upon opposite sides of the rail ends provided with downwardly extending inwardly inclined lugs, a seat for said rail ends positioned between said lugs and provided with inclined ends 30 engageable by said inclined lugs to normally retain said seat in abutting relation with the said rail ends, a truss member underlying said seat and provided with lugs overlying the lugs carried by said fish plates, and 35 means for holding said seat in position relative to the oppositely positioned lugs and in contact with said rail ends.

5. In a rail joint construction, the combination with adjacent rails, of fish plates 40 provided with thickened central portions located substantially opposite the meeting ends of said rails, and oppositely positioned depending lugs located adjacent to the meeting ends of said rails; a seat positioned beneath the meeting ends of said rails and 45 movably secured to said lugs; and a truss member anchored at points remote from the meeting ends of said rails and supporting said seat in contact with the meeting ends 50 of the rails.

6. In a rail joint structure, the combination with adjacent rails, of fish plates positioned upon opposite sides of said rails and provided with oppositely positioned depending lugs located adjacent the meeting ends of 55 said rails, means for securing said fish plates in position upon opposite sides of said rails, a seat located beneath the meeting ends of the rails and between said depending lugs, a 60 truss member underlying said seat and provided with upwardly extending lugs overlying the lugs carried by the fish plates, and fastening devices passed through the oppositely positioned lugs and secured to the 65 seat for retaining said seat in proper posi-

tion relative to the meeting ends of the rails.

7. In a rail joint structure, the combination with adjacent rails, of fish plates secured together upon opposite sides of said rails and provided with oppositely positioned depending lugs located adjacent to the meeting ends of said rails and inwardly inclined downwardly therefrom, a seat located between said depending lugs and provided with inclined ends contacting therewith, fastening means for yieldably connecting said seat to said lugs, and a truss member underlying said seat and supporting the same in contact with said rail ends. 75

8. In a rail joint structure, the combination with adjacent rails, of fish plates secured upon opposite sides thereof and provided with depending inclined lugs located opposite the meeting ends of said rails, each 85 of said lugs being provided with an oblong opening, a seat located between said lugs and provided with inclined ends with which said inclined lugs contact to maintain said seat in contact with the base of said rails, a truss member provided with upturned lugs, and bolts passed through the adjacent lugs and secured in said seat to hold the parts in proper operative position. 90

9. In a rail joint structure, the combination with adjacent rails, of a seat located beneath the meeting ends of said rails, fish plates positioned upon the opposite sides of said rails and provided with depending lugs 95 engaging the ends of said seat below the center thereof, means for exerting pressure upon said lugs to cause the same to grip said seat below the central portion thereof to hold the seat in contact with the rail ends, and a truss member underlying the seat and 100 anchored at points located upon opposite sides of said seat. 105

10. In a rail joint, the combination with adjacent rails, of a seat located beneath the meeting ends of said rails and provided with 110 inclined ends, means underlying the seat and secured to said rails at opposite sides of the seat for supporting said seat, and means for exerting pressure upon the inclined ends of said seat below the central portion thereof 115 to hold the seat in contact with said rail ends.

11. In a rail joint structure, the combination with adjacent rails, of fish plates secured together upon opposite sides of said rails and provided with oppositely positioned depending lugs located adjacent to the meeting ends of said rails and provided with inwardly inclined opposed faces, a seat located between said depending lugs and provided with inclined ends contacting with 120 the inclined faces of said lugs, and a truss member underlying said seat and supporting the same in contact with said rail ends. 125

12. In a rail joint structure, the combination with adjacent rails, of a seat located 130

beneath the meeting ends of said rails and provided with inclined ends, fish plates positioned upon the opposite sides of said rails and provided with depending lugs having inclined faces contacting with the inclined ends of said seat, means for connecting said seat to said lugs to permit limited vertical move-

ment of the seat relative to the lugs and at the same time force the lugs into gripping engagement with said seat to normally hold 10 the seat in contact with the rail ends.

In testimony whereof I have affixed my signature.

JOHN W. CLARK.
